UNITED STATES PATENT OFFICE.

AXEL F. LARSON, OF CHICAGO, ILLINOIS, ASSIGNOR TO WESTERN ELECTRIC PIANO COMPANY, OF CHICAGO, ILLINOIS, A CORPORATION OF ILLINOIS.

AMUSEMENT DEVICE.

Application filed November 30, 1925. Serial No. 72,080.

The present invention relates to amusement devices, and has particular reference to amusement devices adapted for association with a player piano or other mechanically operated musical instrument.

This amusement device is coin-controlled to operate in conjunction with the player piano, the dropping of the coin operating the player piano and also operating the amusement device. During the playing of any selection or selections by the player piano, the amusement device can be operated repeatedly any number of times by the dropping of successive coins. Thus, this amusement device serves to promote the use of the player piano and to increase the revenue derived from the entire machine.

In its preferred embodiment, the present amusement device represents or simulates a horse race, although it will be obvious that it might simulate an automobile race, an aeroplane race, a boxing contest, a game of chance, or a game of skill.

One of the particular objects of the invention is to provide an amusement device of this character which will derive its operating energy from the player piano or other mechanical musical instrument with which it is associated. Another object is to provide such a power operated amusement device which will be coin-controlled in operation.

Another object is to so associate the amusement device with the player piano that the dropping of a coin for operation of the amusement device will be effective to start the player piano, and vice versa.

Another object is to provide an amusement device of this type which can be operated repeatedly by the dropping of successive coins during the playing of the player piano.

Another object is to provide an improved arrangement of impulse mechanism or one-cycle stop mechanism which will transmit a brief operating impulse to the amusement device.

Other objects and advantages will be apparent from the following detailed description of a preferred embodiment of my invention.

50 In the drawing accompanying this embodiment:

Figure 1 is a front elevational view of a typical player piano embodying my invention.

Figure 2 is an interior view of the player piano showing the relation of the parts which co-act in the operation of the amusement device.

Figure 3 is a plan view of one of the inertia wheels for the amusement device, illustrating its ratchet drive from the operating shaft.

Figure 4 is a longitudinal sectional view through the two flywheels or inertia devices for operating the amusement device.

Figure 5 is a sectional view through the primary valve constituting part of the one-cycle stop mechanism, and

Figure 6 is a sectional view through the venting valve which controls the foregoing primary valve.

Figure 1 illustrates a typical coin-controlled player piano in which my invention is embodied. In the upper part of this instrument is provided a show space 11, closed at the front by a glass window 12. In this show space is mounted the amusement device, broadly indicated at 14. Where this amusement device is to simulate a horse race, the background of this show space is preferably illustrated to portray a race track scene. In the foreground, a plurality of racing horses 15-15' are mounted in inner and outer groups, moving in circular paths. In the operation of this amusement device, these two sets of horses are given a spinning motion, and after both sets have come to rest, the horse finishing with its nose closest to the finishing post 16 is considered as having won the race.

Referring now to the operating mechanism for this amusement device, the player piano is of any conventional coin-controlled type, these pianos generally employing an electric motor for their source of power, which electric motor drives the suction bellows or pump and also drives the music sheet in its travel across the tracker bar. This general construction of coin-controlled player piano being old and well known, I have only shown so much thereof as has co-operation with the present amusement device.

The player is set into operation by the insertion of the appropriate coin in the coin slot 18 (Figure 1), which coin slot communicates with a downwardly extending coin chute 19 (Figure 2). This coin chute

19 extends down to a motor switch indicated at 21 adjacent the bottom of the instrument. This motor switch is any suitable coin-controlled type of switch for closing the motor circuit for the playing of one selection. This switch is closed by the dropping of the initial coin, and thereafter during the playing of the desired selection successive coins can be dropped through the coin chute without affecting this switch or the playing of this desired selection.

Referring to Figure 2, a power driven shaft is indicated at 23, this shaft receiving power from the electric motor (not shown) through a driving train in the lower part of the instrument. Part of this driving train is represented by the chain 24 which passes up over the sprocket wheel 25 on the shaft 23. This shaft is representative of any suitable driving element from which power may be transmitted to the present amusement device. In the particular instance shown, this shaft drives the rolls in the tracker box 26, such shaft being a preferred point of power take-off for the amusement device because this shaft always rotates in the same direction and has substantially the desired speed for transmission to the amusement device. The tracker box 26 comprises the usual pair of music sheet rolls, the tracker bar, and clutch and gear mechanism for reversing the rolls, none of which parts are shown as they constitute no part of the present invention.

Referring now to the transmission mechanism for transmitting power from the shaft 23 to the amusement device 14, a grooved pulley 27 is rotatably supported on the shaft 23, this pulley receiving a belt 28. This belt passes up over a second grooved pulley 29 on an upper shaft 31 which drives the amusement device through mechanism which I shall presently describe. The hub of the lower pulley 27 is held against shifting movement on a shaft 23 by collars 33, the shaft normally rotating idly in the hub of the pulley 27. When power is to be transmitted to the amusement device the pulley 27 is clutched to the shaft 23 through a suitable clutch, preferably comprising a clutch collar 34 splined for sliding movement on the shaft 23. This clutch collar has a clutch pin 35 projecting from one side thereof for engagement with a similar clutch pin 36 projecting from the adjacent side of the pulley 27. The clutch collar 34 is arranged to be shifted into and out of clutching position through the motion of an oscillating lever 37 which has a pin 38 engaging in an annular groove in the clutch collar. The lever or arm 37 is pivoted through a pivot pin 39 at its lower end to a bracket arm 41 which is rigidly secured to the side of the instrument case.

The clutch operating lever 37 has a latching pin 42 adjacent its upper end with which

co-operates a pivoted latch 43 having a latching shoulder 44 adapted to engage the pin 42. This latch 43 is pivoted at 45 to an upright standard 46 secured to the bracket arm 41. A leaf spring 47 normally tends to hold the right hand end of the latch down in latching position. When thus held in latched position, the operating arm 37 holds the clutch in disengaged position so that no driving energy is transmitted to the pulley 27. When the latch is tripped, a spring 48 pulls the operating lever 37 to the right and brings the clutch elements into engagement, thereby transmitting driving energy to the pulley 27 and thence up to the amusement device.

The tripping of the latch 43 is performed by the coin falling through the coin chute 19. The right hand end of the latch lever 43 projects through the slot 49 in the coin chute, whereby it lies directly in the path of the descending coin falling through the coin chute. The tripping of the latch 43 permits the coin to continue in its flight down to the motor switch 21.

As soon as the latch 43 is tripped, a driving relation is established between the shaft 23 and the amusement device 14, which driving relation is only maintained for a brief interval sufficient to give the necessary operating impulse to the amusement device. The driving relation is interrupted through the operation of automatic mechanism operating similarly to momentary impulse mechanism, or a one-cycle stop mechanism, which mechanism I shall presently describe.

The rotation imparted to the shaft 31 is transmitted through bevel gears 51 to a vertical shaft 52 which extends up through the shelf or floor 53 defining the bottom of the show space 11. This vertical shaft is journaled in a bearing frame 54 mounted on a lower shelf 55, and in this bearing frame the adjacent end of the horizontal shaft 31 also has bearing support; the opposite end of the shaft 31 having suitable bearing support at the wide wall of the instrument case. Referring to Figure 4, a flywheel 57 is journaled for free spinning motion on the shaft 52 directly above the bearing frame 54 and below the shelf 53. Pinned to the shaft 52 above this flywheel 57 is a ratchet collar 59. Resting on this lower ratchet collar and journaled for free spinning motion on the shaft 52 is an upper flywheel 58. Above this upper flywheel a second ratchet collar 60 is also pinned to the shaft 52. As shown in Figure 3, each of the flywheels 57 and 58 has a pawl 62 pivotally mounted thereon. A spring 63 normally tends to hold the nose of the pawl in the teeth 64 of the respective ratchet collar.

Extending radially from each of the flywheels 57-58 at equidistant points around its circumference, are a plurality of wires or

rods 66-67. The outer ends of these wires are turned upwardly for supporting the miniature horses 15-15' at their upper ends. The upwardly extending ends of the wires 5 67 lie inside of the upwardly extending ends of the wires 66, the upwardly extending ends of both sets of wires passing up through a single circular slot 68 in the shelf 53. Above the shelf, these wires are separated laterally 10 to support their respective horses in two concentric rings spaced slightly one from the other. The central portion of the shelf 53 lying within the circular slot 68 is supported by a wire frame comprising hoops 71 15 which are secured at their outer ends to that portion of the shelf lying outside of the slot and at their inner ends to the central portion of the shelf lying within the slot. The central shaft 52 may be extended up to assist 20 in supporting this frame of hoops 71.

It will be apparent from the foregoing that the rotation of the shaft 31 will set the flywheels 57 and 58 to spinning, and that after the shaft 31 has ceased rotating these 25 flywheels will continue their rotation for a short period by virtue of their overrunning clutch or ratchet drive. It requires only a short operating impulse to set up sufficient momentum in these flywheels for the proper 30 operation of the amusement device. I have found that approximately one complete revolution of the shaft 31 is sufficient to give these flywheels their necessary inertia.

I shall now describe the impulse mechanism or the one-cycle stop mechanism for interrupting the drive to the shaft 31 after the shaft has made substantially one complete revolution. Mounted on the shaft 31 is a collar 74 from which projects a pin 75 40 (Figure 6). After the shaft has made approximately a complete revolution this pin strikes the end of a leaf spring or flap 76 which constitutes the movable element of a venting valve 77. The striking of the pin 45 75 against the leaf spring 76 opens to atmosphere a duct 78 which is normally closed by a valve disc 79 on the leaf spring 76. This duct 78 connects through a conduit 81 with a typical primary valve 82. As shown in 50 Figure 5, this duct 81 opens into a diaphragm chamber 83 closed on its upper side by a flexible diaphragm 84. During the operation of the player piano suction is maintained in a chamber 85 on the upper side of 55 this diaphragm 84, this suction being transmitted through a conduit 86 leading to the feeder bellows or to any suitable source of suction in the instrument. A bleed hole 87 leads from the suction chamber 85 to the 60 duct 81 for normally maintaining suction on the under side of the diaphragm 84. A stem 88 extends upwardly from the diaphragm and serves to actuate valve discs 89 and 90 relative to the suction and atmospheric ports 65 91 and 92. These valve discs and their asso-

ciated ports control the application of suction or atmosphere to a chamber 93 from which leads a conduit 94. With the diaphragm in its lower flexed position atmosphere is admitted to the chamber 93 and conduit 94 through a port 92. With the diaphragm flexed upwardly suction is transmitted to the chamber 93 and conduit 94 through the port 91.

The conduit 94 leads to a bellows 95 or other suction responsive device, the movable element of which has a lost motion connection with a restoring rod 96. This restoring rod has pivotal connection at 97 with the upper end of the clutch operating arm 37. 70 The lost motion connection between the bellows 95 and rod 96 permits the tripping of the clutch operating arm 37 and the engagement of the clutch without interference from the bellows. When the bellows is collapsed, however, by the transmission of suction from the primary valve 82, this lost motion connection retracts the clutch operating arm 37, disengaging the clutch, and relatching 80 the arm with the latch 43.

In the operation of the device the dropping of the first coin through the coin chute 19 will trip the latch 43, establish driving relation between the shafts 23 and 31, and close the motor switch 21 to energize the 90 motor of the player piano. The player piano will then begin operation, playing its selected piece, and the shaft 31 will be rotated to impart stimulus to the amusement device 14. After predetermined movement of 100 the shaft 31 the primary valve 82 will be vented through the duct 81, whereupon the bellows 95 will be collapsed and the clutch operating lever 37 restored to normal position, disengaging the clutch 36-37. Thereafter, the player piano will continue playing 105 its selected tune, or any desired number of tunes (through the proper setting of control mechanism usually provided for this purpose) and the amusement device 14 can be operated any number of times during this continued playing of the piano by the dropping of successive coins through the coin chute 19.

I do not intend to be limited to the particular details herein shown and described, except as they are described in the appended claims.

I claim:

1. In a mechanical musical instrument, a 120 coin chute, latching means released by the dropping of a coin in said chute for controlling the operation of said instrument, a moving element actuated in the playing of said instrument, an amusement device, transmission mechanism for operatively connecting said moving element to said amusement device, resilient means to actuate said transmission mechanism when the same is released by said latching means, and suction 125 130

means for relatching said transmission mechanism in inoperative position after a predetermined period of operation.

2. In a mechanical musical instrument, a coin chute, latching means released by the dropping of a coin in said chute for controlling the operation of said instrument, a moving element actuated in the playing of said instrument, an amusement device, transmission mechanism for operatively connecting said moving element to said amusement device, resilient means to actuate said transmission mechanism when the same is released by said latching means; suction means for relatching said transmission mechanism in inoperative position after a predetermined period of operation and a loose motion connection between said suction means and said transmission mechanism.
3. In a mechanical musical instrument, a coin chute, latching means released by the dropping of a coin in said chute for controlling the operation of said instrument, a moving element actuated in the playing of said instrument, an amusement device, transmission mechanism for operatively connecting said moving element to said amusement device, resilient means to actuate said transmission mechanism when the same is released by said latching means, a source of suction, suction means for returning said transmission mechanism to inoperative position, and a suction controlling device actuated after a predetermined impulse has been given to said amusement device.

4. In a mechanical musical instrument, a coin chute, means responsive to the dropping of a coin in said chute for controlling the operation of said instrument, a moving element actuated in the playing of said instrument, an amusement device, and transmission mechanism for operatively connecting said moving element to said amusement device, said transmission mechanism being controlled by the passage of coins through said coin chute.

5. In a player piano comprising a source of power and a moving element actuated thereby in the playing of the piano, a coin chute, a motor switch responsive to the dropping of a coin in said chute, an amusement device, transmission mechanism for operatively connecting said moving element to said amusement device, means responsive to the passage of coins through said coin chute for rendering said transmission mechanism operative, and automatic means for rendering said transmission mechanism inoperative after a predetermined period of operation.

6. In a player piano, the combination of a moving element actuated in the playing of the piano, a plurality of miniature horses associated with said player piano to simulate a horse race, transmission mechanism for

imparting motion from said moving element to said horses, said transmission mechanism comprising a clutch, a coin chute, a latch responsive to the passage of coins through said chute for permitting engagement of said clutch, a pneumatic for disengaging said clutch, a primary valve controlling said pneumatic, and means responsive to predetermined operation of said transmission mechanism for venting said primary valve. 75

7. In a player piano, the combination of a shaft driven from the electric motor of said piano, a show space associated with said piano; a plurality of miniature horses mounted for rotating movement in said show space to simulate a horse race, a second shaft for rotating said horses, transmission mechanism for operatively connecting said shafts and comprising a clutch on one of said shafts, spring means tending to engage said clutch, a latch normally holding said clutch in disengaged condition, a coin chute, said latch being responsive to the passage of coins through said chute, a pneumatic connected to disengage said clutch, a primary valve controlling said pneumatic, and a venting valve for venting atmosphere to said primary valve after one of said shafts has rotated through a predetermined degree. 80

8. In a player piano, the combination of a tracker box, a shaft extending from said tracker box adapted to be operatively connected to the music sheet rolls therein, a second shaft, power transmission means between said shafts, a clutch on said first shaft for connecting said power transmission means thereto, a clutch operating arm, spring means tending to engage said clutch, a latch effective to hold said clutch operating arm with said clutch in disengaged position, a coin chute, said latch being responsive to the passage of coins through said chute, inner and outer groups of miniature horses mounted for rotating movement in concentric circles, flywheels connected to each group of horses, means for transmitting motion from said second shaft to said flywheels comprising overrunning ratchet mechanism, a pneumatic having a lost motion connection with said clutch operating arm to disengage said clutch when said pneumatic is collapsed, a primary valve controlling the application of suction to said pneumatic, and a venting valve arranged to be opened when said second shaft has completed approximately one revolution to vent atmosphere to the diaphragm of said primary valve. 95

9. In a mechanical musical instrument, a coin chute, means responsive to the dropping of a coin in said chute for controlling the operation of said instrument, a moving element actuated in the playing of said instrument, an amusement device comprising moving figures simulating a race, and transmis- 100

sion mechanism for operatively connecting said moving element to said amusement device, said transmission mechanism being controlled by the placing of coins in said chute.

- 5 10. In a mechanical musical instrument, a coin chute, means responsive to the dropping of a coin in said chute for controlling the operation of said instrument, a moving element actuated in the playing of said instrument, an amusement device comprising con-

centrically moving miniature figures simulating a race, and transmission mechanism for operatively connecting said moving element to said amusement device, said transmission mechanism being controlled by the placing of coins in said chute. 15

In witness whereof, I hereunto subscribe my name this 23rd day of November, 1925.

AXEL F. LARSON.
